UNITED STATES PATENT OFFICE.

JOHN H. WILSON, OF INDIANAPOLIS, INDIANA, ASSIGNOR TO NATIONAL INSULATING AND MFG. CO., OF INDIANAPOLIS, INDIANA.

PIPE-COVERING.

No. 861,927.

Specification of Letters Patent.

Patented July 30, 1907.

Application filed June 23, 1906. Serial No. 323,144.

To all whom it may concern:

Be it known that I, JOHN H. WILSON, a citizen of the United States, residing at Indianapolis, in the county of Marion and State of Indiana, have invented new and useful Improvements in Pipe-Coverings, of which the following is a specification.

This invention relates to a method or process of covering pipes with non-conducting material to prevent the passage of heat or cold either to or from the same, the object of the invention being to provide a process for forming a jointless covering in a simple and inexpensive manner about the pipe, and which will continuously cover the pipe and its fittings or adjuncts and effectually overcome the objections to prior processes or constructions wherein sectional coverings and external fastenings are employed.

The preferred mode of carrying the invention into practice is illustrated in the accompanying drawings, in which,--

26 Figure 1 is a side elevation of a pipe composed of a number of sections and fittings, showing different stages in the process of covering the same. Fig. 2 is a similar view, showing the pipe as it appears when completed. Fig. 3 is a cross section through one of the 25 sections of the completed pipe. Fig. 4 is a detail view of a strip employed in the operation of covering a pipe fitting.

Referring to the drawings, wherein is shown a pipe composed of a number of sections and fittings, the 30 numerals 1, 2, 3 and 4, respectively, represent the sections of the pipe, the sections 1 and 3 being illustrated as connected with the section 2 by couplings or fittings 4', from which suitable branch pipes may lead, and the sections 3 and 4 united by an elbow 5.

35 In Fig. 1, 1 have shown the sections 3 and 4, the couplings 4', and the elbow 5 covered up to the final stage of applying the outer wrapper, while an inner sheet of material is applied in position to be wrapped around the pipe section 2 in the preliminary operation 40 of forming the pipe covering.

In Fig. 2, the operation of covering the pipe is completed.

The method of covering the pipe consists in first laying out a primary sheet of asbestos paper or fabric 6 the 45 length of the pipe to be covered between the fittings or hangers, such as shown in Fig. 1, with relation to pipe section 2. A coating of cement is then applied to the sheet 6 and the latter wrapped around the pipe, the cement fastening the sheet to the pipe and closing the pores of the sheet. Any number of sheets of asbestos 50 may be applied in the same manner according to the thickness desired. A second sheet 7 of wool felt is then coated with cement in the same manner and wrapped around the inner sheet 6, this operation being 55 continued by using a number of sheets or sheets of

different lengths and so applying them until a covering of the requisite thickness is obtained. All the sections of the pipe, including the elbows, are covered in like manner and to the same thickness. The fittings 4' are then covered in like manner with similar strips 8 of 60 asbestos and wool felt and built up to a same thickness as the covering on the pipe proper. Of course, this particular mode of operation of first covering the pipe sections and then covering the fittings may be departed from, and the fittings may first be covered and 65 the sections of the pipe thereafter covered until the applied covering so far described is of uniform thickness throughout the length of the pipe; that is, the covering about the pipe sections is built up to the same level as or so as to lie flush with the covering on the 70 fittings. The covering sheets and strips may be coated on one or both sides with the cement, as desired.

In practice, I may employ any cement suitable for the purpose. Ordinarily, a cement consisting of the following ingredients combined in the proportions 75 stated is used, to wit: Rye flour, 325 pounds; sal-soda, 6 pounds; gum arabic, 3 pounds; alum, 3 pounds; starch, 2 pounds; and lamp black, salt and vitriol (sulfuric acid), each 1 pound. These ingredients are thoroughly mixed by stirring and after being mixed 80 are thoroughly cooked by steam. Such a cement is deemed preferable, as it is not materially affected by extremes of heat or cold, and in connection with the covering is applicable either to pipes used to convey hot water, hot air or steam or to cold water pipes, being 85 effective equally in connection with both.

After the sections and fittings of the pipe have been independently covered in the manner described, an outer binder covering or wrapper 9 consisting of a sheet of some suitable non-conducting material, such as 90 either of those heretofore set forth, is coated with the cement and wrapped around the pipe and fittings continuously along or from end to end of the pipe, thus connecting and binding all of the previously applied wrappings and producing a covering which completely 95 envelops the pipe and all of its portions and which is continuous throughout its length or free from joints which are liable to break apart or to be otherwise injured or are mechanically fastened in the ordinary way. This mode of enveloping the pipe with a non-conducting covering does away with the objectionable practice 100 of using a covering composed of sections enveloping the parts of the pipe and joined or connected by fastenings, and the practice of making the sections to individually fit the sections or portions of the pipe at the factory. The present process may be carried out *in toto* at the time the pipe is to be covered and within the compartment within which it is located, thus enabling the sections of the covering to be cut out to accurately fit the 105 pipe from rolls or sheets of the asbestos and wool felt. 110

Moreover, the covering is superior in point of non-conducting capacity to sectional coverings for obvious reasons.

- In practice, a layer of asbestos is preferably first applied, then a layer of wool-felt, and then another layer of asbestos, etc., until the desired number of layers are applied, such layers of asbestos and wool-felt alternating, as will be readily understood, but this mode of alternately arranging the layers may be departed from 5 after the first layer of wool-felt is applied; in other words, a first layer of asbestos is preferably always used, then a second layer of wool-felt, after which, if more layers are to be applied, asbestos sheets alone may be used.
- 10 15 The purpose of the described arrangement is two-fold: First, a layer of wool-felt, if first applied, would be charred by the heat from high-pressure steam pipes, whereas, by first applying a sheet of asbestos and then a sheet of wool-felt, the asbestos will protect the wool-felt, while the high insulating qualities of the latter, double that of the asbestos, will still be secured. Practical analytical tests have shown that a covering applied in accordance with my invention is superior to the highest quality (85%) magnesia covering, which can 20 25 only be applied in built-up sections, and the use of asbestos and wool-felt under my method also enables pipes to be covered at less cost.
- It is well known that sectional coverings, necessarily made at the factory from measurements, are open to many objections. In a large number of cases the sections do not and cannot be made to fit properly, and on this account, and the fact that mechanical fastenings between the sections are employed at the joints, which are liable to work loose from vibrations of the pipes, the 30 35 insulation does not closely cover the pipe, and the joints often open, thus allowing heat or cold to pass to or from the pipe, resulting in a material loss of efficiency. My process overcomes these objections, as the pipe sections can be accurately fitted and closely covered by the layers, and by building out the pipe sections and hangers or fittings uniformly, the outer continuous wrapper will extend across flush joints, thus enveloping all portions of the pipe so closely as to practically 40 45 avoid all loss of heat or cold. Furthermore, the flush joint construction not only renders the outer cover slightly, but also enables the joints to be securely closed

by the extension of the continuous outer wrapper across the same, thus preventing any possibility of leakage at the joints, since there are no couplings to break or work loose under variations of movement of parts of the pipe 50 from vibrations and other causes.

Having thus described the invention, I claim:—

1. The herein described method of insulating pipes by covering the same with non-conducting material in such a manner as to secure an exteriorly jointless or continuous covering of uniform diameter, the same consisting in laying out a sheet of non-conducting material the length of the pipe to be covered between fittings or hangers, then applying a coating of cement thereto, then wrapping the sheet, so coated, around the pipe, then coating a second sheet of non-conducting material with cement and wrapping the same around the previously applied covering, independently covering the hangers or fittings in like manner until the so covered portions of the pipe are of uniform diameter, and finally cementing and wrapping 60 an outer binding wrapper sheet continuously around the previously applied wrappings, thereby forming a continuous jointless covering.

2. The herein described method of covering a pipe with a non-conducting material, which consists in cutting out wrappers of non-conducting material of a width conforming to the part to which they are to be applied, then covering the sections of the pipe and the fittings thereof with inner and outer cut-out wrappers of different materials until the entire surface of the pipe so covered is uniform 70 in diameter, and then finally applying a single binder wrapping continuously along the pipe over the previously applied wrappers.

3. The herein described method of insulating pipes by covering the same with a non-conducting material so as to secure an exteriorly jointless or continuous covering of uniform diameter, the same consisting in laying out a sheet of non-conducting material the length of the pipe section to be covered between fittings or hangers, then applying a coating of cement thereto, then wrapping the sheet so coated around the pipe, then coating a second sheet of non-conducting material with cement and wrapping the same around the previously applied sheet, independently covering the other sections and hangers or fittings of the pipe in like manner until all the sections 80 85 of the pipe and fittings are of uniform diameter, and finally cementing and wrapping an outer binder wrapper around the previously applied sheets continuously along the entire length of the pipe to form a continuous jointless covering.

In testimony whereof, I affix my signature in presence of two witnesses.

JOHN H. WILSON.
